(57) **CLAIM**

The ornamental design for a rear combination lamp for automobiles, as shown and described.

DESCRIPTION

FIG. 1 is a perspective view of the rear combination lamp for automobiles according to the present invention.

FIG. 2 is a front view of the rear combination lamp for automobiles of FIG. 1.

FIG. 3 is a rear view of the rear combination lamp for automobiles of FIG. 1.

FIG. 4 is a left side view of the rear combination lamp for automobiles of FIG. 1.

FIG. 5 is a right side view of the rear combination lamp for automobiles of FIG. 1.

FIG. 6 is a top view of the rear combination lamp for automobiles of FIG. 1; and,

FIG. 7 is a bottom view of the rear combination lamp for automobiles of FIG. 1.

The broken lines shown in the figures are for the purpose of illustrating portions of the rear combination lamp for automobiles and form no part of the claimed design.

1 Claim, 7 Drawing Sheets
